United States Patent Office

Des. 204,607
Patented May 3, 1966

204,607

ELECTRONIC POWER PACK HOUSING OR SIMILAR ARTICLE

John D. Rutzebeck, P.O. Box 30, Hayward, Calif.

Filed Oct. 20, 1964, Ser. No. 82,249

Term of patent 14 years

(Cl. D26—15)

FIG. 1

FIG. 2

FIG. 3

FIG. 4

FIG. 5

FIG. 1 is a right side elevational view of an electronic power pack housing or similar article, showing my new design, the left side being substantially a mirror image thereof;

FIG. 2 is a top plan view;

FIG. 3 is a front elevational view;

FIG. 4 is a rear elevational view; and

FIG. 5 is a front, top and right-side perspective view thereof.

I claim:

The ornamental design for an electronic power pack housing or similar article, as shown and described.
